DESIGN FOR A SMOKER'S PIPE

Alvin L. Eggers, Denver, Colo.

Application March 12, 1945, Serial No. 118,414

Term of patent 14 years

(Cl. D85—8)

To all whom it may concern:

Be it known that I, Alvin L. Eggers, a citizen of the United States of America, residing at Denver, in the county of Denver and State of Colorado, have invented a new, original, and ornamental Design for a Smoker's Pipe, of which the following is a specification, reference being had to the accompanying drawing, forming a part thereof.

In the drawing:

The dominant features of my new design are shown in full lines in the drawing.

I claim:

The ornamental design for a smoker's pipe, as shown and described.

ALVIN L. EGGERS.
